UNITED STATES PATENT OFFICE.

EDWARD D. ETNYRE, OF OREGON, ILLINOIS.

SPRINKLER-HEAD.

1,179,709.

Specification of Letters Patent. Patented Apr. 18, 1916.

Application filed August 23, 1915. Serial No. 46,793.

To all whom it may concern:

Be it known that I, EDWARD D. ETNYRE, a citizen of the United States, residing at Oregon, in the county of Ogle and State of Illinois, have invented certain new and useful Improvements in Sprinkler-Heads, of which the following is a specification.

This invention relates to sprinkler heads of the type adapted for use in sprinkling 10 water, oil, or other liquids upon a roadway.

The object of the invention is to provide improved means for regulating the direction in which the liquid is discharged, the extent of surface covered by the stream of 15 fluid, and the rate of discharge.

In the accompanying drawings, Figure 1 is a rear elevation of a sprinkler head embodying the features of my invention. Fig. 2 is a vertical central sectional view taken 20 in the plane of dotted line 2—2 of Fig. 1. Fig. 3 is a top plan view. Figs. 4, 5, 6 and 7 are fragmental views showing different adjustments of the sprinkler head.

In the embodiment herein shown, the 25 sprinkler head comprises a cylinder or body 1 having an open lower end and a closed upper end. Upon one side of the cylinder is a nipple 2 by means of which the cylinder may be mounted upon a supply pipe 3. Said pipe constitutes means for supporting 30 the cylinder 1 in vertical position at a suitable point on a sprinkler wagon, as, for example, at the rear end of the wagon. There may be two sprinkler heads at opposite sides 35 of the wagon, or a single sprinkler head may be located centrally upon the wagon. In the rear side of the cylinder 1 near its upper end is a narrow horizontal discharge slot 4. Telescoping with the cylinder 1 is

40 a cylinder 5 having a closed lower end and an open upper end. The cylinder 5 has a port 6 which establishes communication between the supply pipe 3 and the interior of the cylinder 5. In the rear side of the cylinder 5 and near the upper end thereof is a slot 7 which is adapted to register with the slot 4. The slot 7 is somewhat elliptical, being wider at its midportion than at its ends. The inner cylinder 5 may be slid up

50 or down to throw the slot 7 somewhat out of register with the slot 4. To prevent the inner cylinder from turning with relation to the outer cylinder during such sliding movement, I provide suitable means, as, for example, a screw 8 seated in the inner cylinder and projecting through a vertically

elongated slot 9 in the outer cylinder. The means for adjusting the cylinder 5 with reference to the cylinder 1 may be of any suitable construction, that herein shown 60 consisting of a screw 10 pivoted to the lower end of the cylinder 5, said screw extending freely through an opening in a yoke 11 which is fixed to and extends downwardly from the cylinder 1.

65 12 are lock nuts turned on the screw 10 at opposite sides of the yoke 11 to hold the cylinder 5 in adjusted position.

When the cylinder 5 is in the position shown in Figs. 1 and 2, wherein the slots 4 and 7 are in register, the stream of liquid is directed approximately horizontally out through the slot 4. When the cylinder 5 is moved downwardly, as shown, for example, in Fig. 7, the stream is directed upwardly. 70 If the cylinder 5 be adjusted to a point above that shown in Fig. 2, the stream will be directed downwardly. The angle of inclination of the stream may be varied by suitably adjusting the position of the cylinder 5.

The means for entirely or partially cutting off the flow of liquid comprises a cap 13 adapted to fit slidably upon the upper end of the cylinder 1. Said cap has in its 85 rear side an opening 14 (Fig. 1), which opening has a straight lower wall 15, two side or vertical walls 16 and 17, and an upwardly arched or curved upper wall 18. The horizontal dimension of the opening 14 90 may be equal to or slightly in excess of the length of the slot 4. When the cap 13 is in the position shown in Fig. 1, the slot 4 is fully open. The cap 13 may be lowered into the position shown in Fig. 5 in order 95 to entirely close the slot 4, or the cap 13 may be partially lowered to close a greater or less portion of the ends of the slot 4, thus reducing the width of the stream. If it be desirable to interrupt the flow so that the liquid shall be discharged only at one side of the vertical center line of the 100 sprinkler head, the cap 13 may be turned into a position such as that shown in Fig. 6.

The means for operating the cap 13 may be of any suitable character. The means herein shown for turning the cap comprises a rack 19 supported in any suitable manner for horizontal reciprocation, said rack meshing with gear teeth 20 formed upon the 110 cap 13. The teeth 20 are of sufficient length so as to remain in mesh with the rack bar

19 throughout the range of vertical adjustment of the cap. Any suitable means may be provided for reciprocating the rack bar 19.

5 The means for raising and lowering the cap 13 may comprise a lever 21 which is connected by means of a link 22 to a sleeve 23, said sleeve being mounted on the top wall of the cap 13 for rotation upon the 10 axis of said cap. The lever 21 may be operated by any suitable means.

It will be seen that the cap 13 may be raised or lowered to any desired extent, and may at the same time be turned in either 15 direction to a greater or less degree. Said cap thereby affords means for controlling the size of the stream, and also permits the operator to cover any desired portion of the roadway.

20 I claim as my invention:

1. A sprinkler head having, in combination, a cylindrical body having a peripheral horizontally-elongated discharge opening, said body having a closed upper end and an 25 open lower end and an attaching nipple upon its periphery, a cylinder within said body, said cylinder having a closed lower end and an open upper end and a peripheral opening registering with said nipple, said 30 cylinder having an elliptical slot adapted to register with the discharge opening, means to prevent turning movement of the cylinder, and a cap fitting upon the outside of the 35 upper end of the body, said cap being rotatable and axially movable with reference to said body, said cap having a horizontally elongated opening adapted to register with the discharge opening, the opening in the 40 cap having an upwardly curved or arched wall.

2. A sprinkler head having, in combina-

tion, a vertically disposed cylindrical body, means for supplying liquid to said body, said body having a horizontally-elongated 45 discharge opening in its periphery, a member to control the angle of inclination of the discharge, said member being movable transversely of said opening within the body, said member having an elongated opening arranged to register with the first mentioned opening, the middle portion of one of said openings being wider than the middle portion of the other opening, means for vertically adjusting said member and a member 50 movable upon the outside of the body to cover and uncover more or less of the discharge opening.

3. A sprinkler head having, in combination, a vertically disposed cylindrical body 60 provided with a horizontally-elongated discharge opening, a cap fitting upon the outside of the body and movable longitudinally and transversely of said discharge opening, said cap having an arched opening therein 65 arranged to expose the discharge opening and mechanism for rotating and axially sliding said cap.

4. A sprinkler head having, in combination, a cylindrical body having an elongated 70 discharge opening, and a controlling member which is rotatable and axially movable with reference to said body, said controlling member having an elongated opening adapted to register with the first mentioned opening, the second mentioned opening having a curved or arched wall.

In testimony whereof, I hereunto set my hand in the presence of two witnesses.

EDWARD D. ETNYRE.

In the presence of—
CLARENCE S. HAAS,
SUE CARL.
